MATRIX-DELIVERY MECHANISM FOR LINE-COMPOSING MACHINES.

1,146,653.

Specification of Letters Patent.

Patented July 13, 1915.

Application filed June 9, 1913. Serial No. 772,720.

To all whom it may concern:

Be it known that I, KIRBY S. REIST, a citizen of the United States, residing at San Francisco, in the county of San Francisco and State of California, have invented new and useful Improvements in Matrix-Delivery Mechanism for Line-Composing Machines, of which the following is a specification.

10 This invention relates to improvements in machines of the type wherein matrices are assembled to form a line from which a slug or type bar is cast and is applicable particularly to machines of the well known linotype class.

The primary object of the invention is to provide a set of escapement devices which are located wholly forward of the delivery end of the magazine and form continuous channels without openings therein, enabling the use of two or more magazines, any one of which may be brought into operative relation with the set of escapement devices to deliver matrices as required without the necessity of using complicated connecting and disconnecting mechanism, the escapement devices being preferably mounted on the main frame of the machine and the different magazines movable to and from operative relation therewith.

To this end, the invention consists in certain improvements, and combinations and arrangements of parts, all as will be herein-after more fully described, the novel features being pointed out particularly in the claims at the end of the specification.

The accompanying drawing illustrates one embodiment of the invention, it representing a vertical section through the delivery ends 40 of the magazines and illustrating the relation between the magazines and the set of escapement devices.

In the present instance, a set of three magazines designated 1, 2 and 3 is illustrated, these magazines being inclined, as usual, in order that the matrices contained in the channels thereof may gravitate to the delivery ends thereof, and a set of escapements 4 is employed, these escapements being arranged in a row and are mounted to rock on a pivot pin 5. Preferably, the escapements are mounted on or arranged in fixed relation to the main frame of the machine, the pivot pin 5 being preferably sup-

ported on the main frame. Each escapement is provided with front and rear pawls 6 and 7 which coöperate with and control the delivery of matrices, and a spring 8 is provided for each escapement and operates to return the escapement to the position shown in the drawing after each actuation thereof and to retain the escapement in such position. The magazines are shiftable bodily in a direction at right angles to the channels therein, and the delivery ends of those magazines which are not in use are closed and the matrices retained therein by a plate 9 which lies in front of the delivery ends of the magazines and is parallel to the direction in which the magazines are shiftable. This plate is secured to a frame 10 which is stationary and the magazines are shiftable in relation thereto. The plate 9 is formed with an opening 11 through which matrices may be delivered from any one of the magazines when brought into operative relation to the escapement devices. Upper and lower channeled guides 12 and 13 are provided, these guides extending downwardly and forwardly from the opening 11 in the plate 9 and forming uninterrupted continuations of the channeled top and bottom plates of the magazine when the latter is in operative position. The pawls 6 and 7 of the escapements operate through openings in the lower guide 13, the forward or lower pawl 6 when elevated occupying a position to engage the lower or forward lug on a matrix contained between the guides 12 and 13, and the rear or upper pawl 7 of each escapement is adapted when elevated to coöperate with the lower or forward lug on the foremost or leading matrix contained in the magazine being used. This upper rear pawl 7 on the escapement is also shaped and arranged to prevent the foremost or leading matrix in any of the magazines from entering the opening 11 while the magazines are being shifted past the opening 11 in the matrix-retaining plate 9. The matrices when released by the escapements enter the assembler guides 14 and may be assembled into a line in the usual well known manner. The escapements are preferably operated from a keyboard, as usual, a vertically movable escapement rod 15 being shown in the present instance which coöperates with a lug 16 on the respective escapement, the lower end of

this escapement rod being pivotally connected to a lever 17 mounted on a pivot 18, and a key-rod 19 operative by the keyboard is adapted to coöperate with the rear end of the lever 17. Normally, each escapement will occupy the position shown in the drawing, the rear pawl 7 then occupying a position to engage the lower or forward lug on the foremost matrix in the magazine in use. Lifting of the key-rod 19 by manipulation of the keyboard causes downward movement of the escapement bar 15, thereby rocking the escapement 4 and lowering its rear pawl 7 below the matrix in the magazine which rests against it, this movement of the escapement also elevating its forward pawl 6 into the path of the matrix. The matrix thus freed descends until its front lug comes against the forward pawl of the escapement, whereupon the key-rod returns to its normal position and the escapement is returned to the position shown in the drawing by the action of the spring 8. The rear pawl 7 of the escapement then enters a cut-out portion 25 M' formed in the matrix M, this matrix being then just outside of the magazine. The return movement of the escapement lowers the forward pawl 6 thereon from the path of this matrix and thus permits the same to fall into the assembler guides 14.

By shifting the magazines, any one of them may be brought into operative relation with the escapement mechanism, the matrices in the other magazines not in use being retained by the plate 9. Any suitable means may be used for shifting the magazines, such for example, as that shown in the patent to P. T. Dodge, No. 548,432 dated October 22, 1895.

By mounting the escapements in front and independently of each magazine, and shifting the magazines to bring them as desired into operative relation with the escapements, a very simple and reliable arrangement is provided which enables the operator to use matrices from any of the magazines and which avoids the necessity of employing complicated connecting and disconnecting mechanism for the escapements. The expense of providing each magazine with a set of escapements is also avoided.

I claim as my invention:—

1. In a machine of the linotype class, the combination of the magazine having a set 55 of channels to store the matrices in columns, a set of escapements, one for each magazine channel, each escapement being located forward of its corresponding column of matrices, the magazine and escapements being relatively shiftable to render the magazine operative and inoperative, and means operative to close and retain the matrices in the delivery end of the magazine when the latter is in inoperative position, the escapements 60 being normally operative to hold the mat-

rices in the magazine with their lower ends in the plane of said matrix-retaining means.

2. In a machine of the linotype class, the combination of the magazine having a set of channels to store the matrices in columns, a 70 set of escapements, each having a pair of retaining pawls adapted to move alternately into and out of the pathway of the matrices, the rear or upper pawl of each escapement being normally in front of the leading matrix in the respective column, the magazine being shiftable into operative and inoperative positions relatively to the escapements, and means lying in the plane of the rear or upper pawls of the escapements for retaining the matrices in the delivery ends of the magazine when the latter is in inoperative position.

3. In a machine of the linotype class, the combination of a set of matrix-controlling escapements, a plurality of matrix-containing magazines movable relatively to the escapements, each magazine with its matrices being located wholly above or in rear of the escapements, and a plate arranged to cover the delivery ends of the magazines not in use and having an opening to admit matrices to the escapements from the magazine in use, the portions of the escapements controlling the discharge of matrices from the magazine 95 operating to automatically position the forward ends of the matrices to coöperate with said plate.

4. In a machine of the linotype class, the combination of a magazine having channels 100 to contain matrices, a set of escapements located wholly in front of and mounted independently of the magazine for controlling the delivery of matrices therefrom, the magazine being shiftable relatively to the escapements, and means in fixed relation to the escapements for retaining the matrices in the magazine when the latter is shifted out of operative relation with the escapements, the escapements acting to automatically position 110 the matrices in the magazine to coöperate with said retaining means.

5. In a machine of the linotype class, the combination of a magazine having channels to contain matrices, a set of escapements for controlling the delivery of matrices therefrom, the magazine and escapements being relatively movable to and from operative relation and the escapements being mounted independently of the magazine, and a plate 115 in fixed relation to the escapements and lying in the plane of the upper ends thereof to retain the matrices in the delivery end of the magazine when the latter is in inoperative relation to the escapements.

6. In a machine of the linotype class, the combination of a magazine having channels to contain matrices, a set of escapements for controlling the delivery of matrices therefrom, the magazine being movable to and 130

from operative relation with the escapements and the escapements being mounted independently of the magazine and in front thereof, the escapements being operative to control the delivery of matrices from the magazine when the latter is in operative position, and means lying in the plane of the upper ends of the escapements and operative to retain the matrices in the magazine when the latter is in inoperative position.

7. In a machine of the linotype class, the combination of a set of escapements, a plurality of magazines movable relatively to the escapements to bring any one of them in operative relation therewith, and a plate in fixed relation to the escapements and lying in the plane of the upper ends thereof for retaining matrices in the magazines when not in operative relation with the escapements.

8. In a typographical machine, the combination of a magazine to contain the matrices and movable to and from operative position, a series of escapements mounted independently of the magazine and beyond its delivery end to control the passage of the matrices therefrom, the upper end of each of the escapements normally engaging the lower end of the lowermost matrix to hold

it within the magazine, and a plate in fixed relation to the escapements and lying in the plane of the upper ends thereof to retain the matrices in the magazine when the latter is in inoperative position.

9. In a typographic machine, the combination of a plurality of magazines to contain the matrices and movable as a whole to bring any selected one into operative position, an assembling throat to receive the matrices from the operative magazine, a series of escapements acting in said throat to control the passage of the matrices therethrough, the upper end of each of said escapements normally engaging the lower end of the lowermost matrix to hold it within the operative magazine, and a plate lying in the plane of the upper ends of the escapements and operative to retain the matrices in the magazines which are in inoperative position.

In testimony whereof I have hereunto set my hand in presence of two subscribing witnesses.
